ADJUSTABLE SHOE TREE

Charles A. Traurig, Flushing, N. Y.

Application October 27, 1944, Serial No. 560,534

2 Claims. (Cl. 12—128.6)

This invention relates to new and useful improvements in adjustable shoe trees.

More specifically, the invention proposes a new and improved shoe tree which is characterized by a vamp-like member for engaging in the vamp portion of a shoe and having a slot with vertical parallel opposed faces and extending inwards from its rear end. A heel engaging toggle is provided for engaging the heel portion of said shoe and consists of a yoke-like wire member pivotally connected with a cam-like heel engaging member. The invention proposes certain means for pivotally and adjustably connecting said yoke-like wire member upon the opposed faces of the slot in said vamp-like member.

In one form of the invention the opposed faces of said slot are formed with openings into which outwardly directed ends of the wire member are engaged. In another form of the invention plates with openings are adjustably mounted on the opposed faces of the slot, and the out turned end portions of the wire member pivotally engage in the openings of said plates.

Still further the invention proposes the construction of an adjustable shoe tree which is simple and durable and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an adjustable shoe tree constructed in accordance with this invention.

Fig. 2 is an elevational view of the shoe tree shown in Fig. 1 with the heel engaging toggle in a different position.

Fig. 3 is a bottom view of Fig. 2.

Fig. 4 is a fragmentary plan view of an adjustable shoe tree constructed in accordance with a modified form of this invention.

Fig. 5 is a vertical sectional view taken on the line 5—5 of Fig. 4.

Fig. 6 is a fragmentary vertical sectional view taken on the line 6—6 of Fig. 5.

The adjustable shoe tree, in accordance with that form of the invention disclosed in Figs. 1 and 2, includes a vamp-like member 10 for engaging in the vamp portion of a shoe. This member 10 is provided with a slot 11 which is extended inwards from its rear end and its bottom side.

The slot 11 has vertical parallel opposed faces which are formed with a plurality of openings 12 arranged in substantial horizontal line.

A heel engaging toggle is associated with the vamp-like member 10 and is formed from two parts, namely a yoke-like wire member 14 and a cam-like heel engaging member 15. The wire member 14 is of U-shape having a pair of side arms 16 and a central connecting portion 17. The outer ends of the arms 16 are pointed or directed outwards and are engaged in an opposed pair of the openings 12 in the opposed faces of the slot 11.

The central connecting portion 17 of the wire member 14 is pivotally connected with the cam-like heel engaging member 15. A bracket 18 is mounted upon the side of the cam-like heel engaging member 15 and is provided with a socket portion 19 through which the central connecting portion 17 pivotally engages.

The cam-like heel engaging member 15 has a rounded bottom end 20 and a pointed top end 21. When the shoe tree is engaged in a shoe, the yoke-like wire member 15 is adjusted to the size of the shoe by engaging the out turned ends of the arms 16 in a proper pair of the openings 12. This may be done by pressing together the outer ends of the arms 16 so as to disengage the out turned end portions from the openings 12 which they are engaging and then they may be re-engaged in a desirable pair of said openings 12. When the top end 21 of the cam-like heel engaging member 15 is pivoted towards the vamp-like member 10, the bottom end 20 will be cammed against the heel portion of the shoe and together with the wire engaging member 14 will stretch or straighten out the shoe.

In Figs. 4 to 6 inclusive a modified form of the invention has been disclosed which is very similar to the prior form distinguishing merely in the manner in which the yoke-like wire member 15 is pivotally connected with the vamp-like member 10. In this form of the invention there are side plates 22 which are adjustably mounted upon the opposed faces of the slot 11. The side plates 22 are provided with slots 23 through which studs 24 engage. These studs 24 are mounted upon and projected from the opposed faces of the slot 11. The studs 24 are provided with nuts 25 by which the plates 22 may be held in selected vertical positions. The slots 23 are disposed substantially vertical. The plates 22 are formed with a series of openings 26 substantially on a horizontal line. The outer ends of the arms 16

of the wire member 14 are engaged selectively in a pair of the openings 26.

The dominating feature of this form of the invention resides in the fact that the toggle action of the heel engaging toggle may be better adjusted for accommodating the shoe tree for a specific size of shoe. Not only can the free ends of the arms 16 be engaged in selected openings 26 but the elevation of these openings 26 may be adjusted by vertically adjusting the plates 22.

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new and desire to secure by United States Letters Patent is:

1. An adjustable shoe tree, comprising a vamp-like member for engaging in the vamp portion of a shoe and having a slot with vertical parallel opposed faces and extending inwards from its rear end, a heel engaging toggle for engaging in the heel portion of said shoe and consisting of a yoke-like wire member pivotally connected with a cam-like heel engaging member, and means for

pivottally and adjustably connecting said yoke-like wire member upon said opposed faces, comprising plates vertically adjustably mounted upon the opposed faces of said slot and being formed with a horizontal line of openings, and said wire member having end portions pivotally engaging in a pair of said openings.

2. An adjustable shoe tree, comprising a vamp-like member for engaging in the vamp portion of a shoe and having a slot with vertical parallel opposed faces and extending inwards from its rear end, a heel engaging toggle for engaging in the heel portion of said shoe and consisting of a yoke-like wire member pivotally connected with a cam-like heel engaging member, and means for pivotally and adjustably connecting said yoke-like wire member upon said opposed faces, comprising plates vertically adjustably mounted upon the opposed faces of said slot and being formed with a horizontal line of openings, and said wire member having end portions pivotally engaging in a pair of said openings, said plates having vertical slots, and studs being mounted upon said opposed faces and engaging through said slots and provided with nuts by which said plates may be held in adjusted positions.

CHARLES A. TRAURIG.
